COUPLING DEVICE FOR ROAD FORMS

Harry E. Holford, Binghamton, N. Y., assignor
to Binghamton Foundry & Machine Co. Inc.,
Binghamton, N. Y., a Corporation of New
York

Application May 25, 1931. Serial No. 539,862

2 Claims. (Cl. 25—118)

My invention relates to a coupling device for road forms and has for its primary object the provision of a coupling which tends to insure the proper alignment of the adjacent ends of the forms or rails.

Another object of my invention is to provide a coupling which is extremely simple in operation and provided with a securing means for rigidly locking the coupling in rail joining position but permitting ready uncoupling for dismantling.

A further object of my invention is to provide a coupling in which the adjacent or joining ends of the forms are cut on a bias whereby the assembly thereof is facilitated.

Other objects and advantages in details of construction and arrangement of parts will be apparent as the description proceeds, reference now being had to the figures of the accompanying drawing forming a part of this application and wherein like reference numerals indicate like parts.

In the drawing:

Figure 1 is a detail side elevation illustrating my improved coupling in secured position, certain parts being broken away for clearness of illustration.

Figure 2 is a cross sectional view taken on the line 2—2 of Figure 1.

Figure 3 is a detail sectional view taken on the line 3—3 of Figure 1.

The reference characters 1 and 2 refer generally to adjacent ends of sections of metal road forms such as are used in the construction of concrete highways, sidewalks, and the like, the use of such sections being well known in the art and requiring no detailed description. Suffice it to say, that these sections are laid end to end and in proper parallel alignment for the purpose of defining the shoulders of the roadway, the road material being filled in between the rails or forms and properly processed until the cement or other material has been set, whereupon the form sections are disconnected and re-assembled for use on the next strip of road to be built.

The rails or forms are of the general shape and type shown in section in Figure 2 and comprising the bottom flange 3, the vertical web portion 4, the top horizontal flange 5, and the vertical depending flange 6, extending downwardly from the top.

In accordance with my invention the ends of the rail sections to be joined are cut on an angle as at 7, such as from a point even with the lower

edge of the depending flange 6, to the bottom flange 3.

Suitably secured to the end of the rail section 1 and conforming to the flanged configuration thereof, is an anchor plate member 8 having a bottom flange 9 and a downwardly depending flange 10, said plate and its flanges fitting closely within the flanges of the rail section 1 and being suitably rigidly secured thereto as by riveting, welding or otherwise.

The outer edge of this anchor plate member 8 extends beyond the angular end of the rail section 1 as shown clearly in Figure 1, except at the lower edge of the rail section where the anchor plate 8 falls short of such angle end. This is illustrated clearly at 11 in Figure 1. Consequently at the upper edge of the assembly the anchor plate 8 projects beyond the angular end of the section whereas at the lower edge such plate falls substantially short of such angular end.

The end of the section 2 is likewise provided with an anchor plate 12 conforming to the flanged shape of the section 2 and provided with the bottom flange 13, the upper horizontal flange 14, and the upper depending vertical flange 15. This plate 13 is likewise rigidly secured to the end of the rail section 2 and the upper portion of this plate 12 is spaced substantially inwardly from the angular end of the section whereas the lower portion of the plate extends beyond the lower angular portion of the rail section as at 16.

By means of this construction, when the adjacent ends of the sections 1 and 2 are to be joined, the section 2 may be lowered into abutting position with the end of section 1, assuming section 1 to be placed and fixed in proper position, in which position it will be noted that the upper flanges 5 and 6 of the rail section 2 hook directly over the corresponding upper flanges of the anchor plate 8 which project beyond the end of the section 1. Likewise the lower flange 13 of the plate 12 overlies and rests upon the bottom flange 3 of the section 1. The angular end portions of the sections 1 and 2 are thus brought into direct abutting engagement.

By this simple arrangement the rail sections may be carried to assembly position and lowered directly into proper engagement with the adjacent rail section.

It may be noted here that the anchor plates 8 and 12 in addition to providing a fastening means for the rail sections serve as reinforcing means for the sections at these points.

The anchor plate 8 is provided intermediate its ends and adjacent its outwardly projecting edge, with a lug or boss 17 extending outwardly from the plate and undercut as at 18 at its lower end for a purpose to be described. The position of this lug 17 is approximately on the angular line of joinder of the rail sections 1 and 2.

Pivoted at 19 on the plate 12 is a hook 20 having the locking portion 21 at its free end and adapted for engagement with the undercut portion of the lug 17. The lower end of the hook member is provided with a laterally projecting lug 22 providing a manipulating member whereby the hook may be driven into locking frictional engagement with the lug 17.

The shape of the locking portion of the hook is such with respect to the angular disposition of the lug 17 that a relatively long locking surface is provided and of such character that when the hook is driven to locking position the adjacent ends of the rail sections 1 and 2 are automatically brought to proper alignment, in which position they are rigidly secured until it is desired to again dismantle the rail sections.

For such dismantling it is necessary merely to drive the hook member out of locking engagement whereupon the rail section 2 may be lifted vertically free of the section 1.

I have thus provided a novel, simple, and rigid coupling means for joining the ends of road rail or form sections, having no loose parts to be car-

ried with the rail sections and which may be quickly and easily operated to provide a properly aligned form or rail.

Of course, changes may be made in details of construction and arrangement of parts without departing from the spirit and scope of my invention. I do not limit myself, therefore, to the exact form herein shown and described other than by the appended claims.

I claim:

1. A road form comprising rail sections adapted for end-to end coupling, the abutting ends of said sections being formed on a bias longitudinally of the sections, and means on the abutting ends of said sections for drawing said sections into alignment and for locking them in such position, said means comprising a lug on one of said ends and a hook on the other of said ends for locking engagement with said lug.

2. A road form comprising a rail section having an end formed on a bias for abutting engagement with a similarly but oppositely formed end of a second section, anchor plates fixed to the abutting ends of said sections and having portions projecting beyond said ends for interengagement when said sections are joined, a lug carried by one of said plates and a hook carried by the other adapted for locking engagement with said lug whereby said sections may be secured together in aligned position.

HARRY E. HOLFORD.
